United States Patent Office

Des. 179,709
Patented Feb. 12, 1957

179,709

BUILDING OR SIMILAR ARTICLE

Bonnie Smith, Jr., Philadelphia, Pa.

Application March 12, 1956, Serial No. 40,615

Term of patent 14 years

(Cl. D13—1)

FIG. 1

FIG.4

Fig. 1 is a perspective view of a building or similar article, showing my new design;

Fig. 2 is a plan view;

Fig. 3 is a front elevational view; and

Fig. 4 is a rear elevational view thereof.

I claim:

The ornamental design for a building or similar article, substantially as shown.
